C. L. BRALEY,
LAUNDRY TRUCK,
FILED Oct. 8, 1921.

UNITED STATES PATENT OFFICE.

CHARLES L. BRALEY, OF CHICAGO, ILLINOIS, ASSIGNOR OF ONE-HALF TO CHARLES F. NOFTZGER, OF CHICAGO, ILLINOIS.

LAUNDRY TRUCK.

Application filed October 8, 1921. Serial No. 506,434.

To all whom it may concern:

Be it known that I, CHARLES L. BRALEY, a citizen of the United States, residing at Chicago, in the county of Cook, State of Illinois, have invented certain new and useful Improvements in Laundry Trucks, of which the following is a specification.

This invention relates to improvements in laundry trucks.

10 The main object of this invention is to provide an improved laundry truck by means of which laundry may be conveniently handled or moved from one laundry machine to another, as, for instance, from a washing machine to an extractor.

15 A further object is to provide an improved laundry truck which also serves as a drainer, making it convenient to discharge the water into a gutter or catch-basin at the desired location.

20 Further objects, and objects relating to details and economies of construction and operation will definitely appear from the detailed description to follow.

25 I accomplish the objects of my invention by the devices and means described in the following specification. The invention is clearly defined and pointed out in the claims.

30 A structure which is a preferred embodiment of my invention is fully illustrated in the accompanying drawing forming a part of this specification, in which:

35 Fig. I is a side elevation of my improved laundry truck, parts being broken away to show structural details, the basket being shown in elevated or discharging position by dotted line. The truck is shown conveniently in operative relation to a washing machine.

40 Fig. II is a front view of my improved laundry truck parts being broken away to show structural details.

45 Fig. III is a detail vertical section on a line corresponding to line 3—3 of Fig. I, showing details of the basket supporting bracket.

50 Fig. IV is a detail section on a line corresponding to line 4—4 of Fig. II.

55 In the drawing similar reference numerals refer to similar parts throughout the several views.

Referring to the drawing, I provide a running gear comprising a frame 1 and legs 2, provided with wheels 3 and 4. The wheel

4 is a caster wheel. On this running gear is a tank-like receptacle 5 of general rectangular cross section in a horizontal plane. At the upper front corner of this tank I pivot at 6 the foraminated basket 7. This 5 basket may be lowered into the receptacle as indicated in full lines in Figs. I and II, or elevated to discharging position as shown by dotted lines in Fig. I; in which position its bottom 8 is inclined toward the pivot, 60 thereby facilitating the discharge of the contents. The basket is of triangular cross section in the vertical plane from front to rear, the pivot being at the front angle of the basket. 65

The receptacle is provided with a drain cock 9 to which a hose may be attached if desired, so that the water may be discharged from the receptacle into a drain or the truck 70 may be run over a catch basin. The truck 75 may thus be utilized as a drainer.

To support the basket in discharging position, I provide the bracket 10 having a rest 11 which swings under the basket when it is elevated as is shown in Fig. III. To 80 assist in raising the basket, I provide a block and tackle designated generally by the numeral 12, the tackle being secured to the rear upper corner of the basket and supported by an arm 13 on a bar 14. The bar is provided at one of the rear corners of the running gear frame so as to be out of the way. 85

In use the truck is backed up to a washer as indicated at 15, the washing pulled into the basket, the basket being then in lowered 90 position. The truck is then moved to discharging position and the laundry pulled from the basket into the extractor 16. To facilitate the transfer of the wash from the basket to the extractor or other laundry machine, I provide a chute 17 which is mounted on the pivot 6 so as to be swung outward to the position shown by dotted lines in Fig. 95 IV and thereby constituting a bridge between the basket and the machine to which the articles are discharged.

In practice it is found that considerable of the water has drained from the wash while in the basket and the receptacle holds this drainage until it is drawn off at the 105 desired point. This is of very material advantage as it prevents the floor of the laundry from becoming sloppy and wet by the transfer of wet goods such as now commonly results.

I have illustrated and described my improvements in an adaptation which I find very practical. I have not attempted to illustrate or describe other modifications or adaptations as I believe the disclosure made will enable those skilled in the art to which my invention relates to embody or adapt the same as may be desired.

Having thus described my invention, what I claim as new and desire to secure by Letters Patent is:

1. In a laundry truck, the combination with a running gear, of a receptacle on said running gear, a foraminated basket pivotally mounted at one side of said receptacle to be lowered therein or raised therefrom, the bottom of said basket being disposed so that when the basket is in raised position the bottom is inclined towards the pivot to facilitate the discharging of the contents of the basket, a bracket provided with a rest for holding said basket in its discharging position, and a hoisting means for said basket.
2. In a laundry truck, the combination with a running gear, of a receptacle on said running gear, a foraminated basket pivotally mounted at one side of said receptacle to be lowered therein or raised therefrom, the bottom of said basket being disposed so that when the basket is in raised position the bottom is inclined towards the pivot to facilitate the discharging of the contents of the basket, and a hoisting means for said basket.
3. In a laundry truck, the combination with a running gear, of a receptacle on said running gear, a foraminated basket pivotally mounted at one side of said receptacle to be lowered therein or raised therefrom, the bottom of said basket being disposed so that when the basket is in raised position the bottom is inclined towards the pivot to facilitate the discharging of the contents of the basket, and a bracket provided with a rest for holding said basket in its discharging position.
4. In a laundry truck, the combination with a running gear, of a receptacle on said running gear, and a foraminated basket pivotally mounted at one side of said receptacle to be lowered therein or raised therefrom, the bottom of said basket being disposed so that when the basket is in raised position

the bottom is inclined towards the pivot to facilitate the discharging of the contents of the basket.

5. In a laundry truck, the combination with a running gear of a basket of triangular vertical cross section pivotally mounted on said running gear at one of its upper angles so as to be raised and lowered and so that when in raised position its bottom is inclined towards its pivot for discharging the articles therefrom, and a pivoted chute mounted to be swung outwardly beyond the basket.

6. In a laundry truck, the combination with a running gear of a basket of triangular vertical cross section pivotally mounted on said running gear at one of its upper angles so as to be raised and lowered and so that when in raised position its bottom is inclined towards its pivot for discharging the articles therefrom, a rest for holding said basket in its discharging position, and a hoisting means for said basket.

7. In a laundry truck, the combination with a running gear of a basket of triangular vertical cross section pivotally mounted on said running gear at one of its upper angles so as to be raised and lowered and so that when in raised position its bottom is inclined towards its pivot for discharging the articles therefrom, and a hoisting means for said basket.

8. In a laundry truck, the combination with a running gear of a basket of triangular vertical cross section pivotally mounted on said running gear at one of its upper angles so as to be raised and lowered and so that when in raised position its bottom is inclined towards its pivot for discharging the articles therefrom, and a rest for holding said basket in its discharging position.

9. In a laundry truck, the combination with a running gear of a basket of triangular vertical cross section pivotally mounted on said running gear at one of its upper angles so as to be raised and lowered and so that when in raised position its bottom is inclined towards its pivot for discharging the articles therefrom.

In witness whereof, I have hereunto set my hand and seal.

CHARLES L. BRALEY. [L.S.]
